UNITED STATES PATENT OFFICE.

EDWIN CROMPTON AND CHARLES L. CROOKS, OF PUEBLO, COLORADO.

LATCH.

1,281,143.

Specification of Letters Patent.

Patented Oct. 8, 1918.

Application filed April 15, 1918. Serial No. 228,529.

To all whom it may concern:

Be it known that we, EDWIN CROMPTON and CHARLES L. CROOKS, citizens of the United States, and residents of Pueblo, in 5 the county of Pueblo and State of Colorado, have invented certain new and useful Improvements in Latches, of which the following is a full, clear, and exact description.

Our invention is an improvement in latches 10 and, while of general applicability, it is especially adapted for use on automobile doors. The principal object of our invention is the provision of a combined latching and locking device, in which both the latching 15 and locking operations are automatically performed by the act of closing the door and in which a single movement will both unlatch and unlock without the use of keys or the like. Further and more particular 20 objects and advantages of our invention will later appear from this specification.

In the single sheet of drawings accompanying this application and forming a part hereof

25 Figure 1 is a vertical section through a latch and keeper embodying our invention, the section through the keeper being taken on the line 1—1 of Fig. 4, and the parts being shown in locked position;

30 Fig. 2 is a view similar to Fig. 1 except that the keeper is shown in side elevation and the parts in unlocked position;

Fig. 3 is a horizontal section taken on the line 3—3 of Fig. 1; and

35 Fig. 4 is a face view of the keeper.

Referring to the drawings, in which like characters designate like parts in the several views, it will be seen that our latch comprises a casing having parallel side mem-

40 bers 10, a face plate 11 and preferably open at the rear. The side plates 10 are joined by upper and lower transverse braces 12 which also serve as guides for the plunger 13. This plunger is preferably reduced at

45 its lower end as shown and encircled by a spring 14 which tends to hold the plunger in elevated position. The plunger 13 is pro- vided with a stop 15 adapted to engage the underside of the upper brace 12, thus limit-

50 ing upward travel of the plunger, and also with a knob or handle 16 on its upper end which is located in convenient position in the upper surface of the door so that it may be engaged and depressed manually to free 55 the latching and locking mechanism.

The latching mechanism comprises a leaf

spring 17 secured at its lower end to the inner side of the face plate 11 and carrying at its upper end a substantially semi-spherical knob 18. The knob 18 is so located 60 as to travel in a circular recess 19 in the face plate 11, being substantially withdrawn therethrough when the leaf spring 17 is forced back.

The preferred form of keeper for use 65 with our latch is shown in face view in Fig. 4 and in side view in Fig. 2. This keeper comprises a face plate 20 having a semi-spherical recess 21 therein and provided on the side toward which the door opens with 70 an inclined surface 22 opposite the recess 21. The upper end of the keeper plate is bent back out of the plane of 20 and is provided with a cam lug 23 whose outer face stands substantially in the plane of the face 20. 75 The cam face 24 of the lug 23 is presented toward the side to which the door opens and this lug does not extend, as shown in Fig. 4, farther than a point substantially 80 where the socket 21 starts.

The plunger 13 carries rigidly projecting therefrom a finger 25 which extends outwardly and at an angle upwardly and projects from the front of the casing through a slot 26 therein, being provided on its outer 85 extremity with a substantially spherical head 27. Rigidly mounted on a transverse spindle 28, journaled in the side members 10, there is a second finger 29 which is connected by a pin and slot to the plunger 13 90 and which has its outer extremity in position to contact with and lock the leaf spring 17 when in horizontal position.

Operation.

95

From inspection of Fig. 1, which shows the parts in lock position, it will be evident that in this position there is provided a double locking means for the door. These locking means comprise first, the knob 18 100 which is home within the recess 21 and which is held in that position by the finger 29; and, second, the finger 25 which in this position is behind the vertical surface 30 on the lug 23 of the keeper. If pressure be 105 exerted on the knob 16 and the plunger 13 depressed the finger 25 will be so lowered as to clear the surface 30 and the finger 29 will be depressed to the position shown in Fig. 2 which frees the leaf spring 17. If 110 now the parts be held in this position a gentle pressure against the door will cause

the knob 18 to be forced out of its socket as indicated in Fig. 2 and the door may be opened. If now the knob 16 be released the spring 14 will return the latch parts to the 5 position of Fig. 1. If the door be forced shut the head 27 of the finger 25 will first engage the cam surface 24 on the lug 23. This will depress the plunger 13 and will free the spring 17 to permit the knob 18 to 10 pass over the surface 31 on the keeper. When the door is fully closed the knob 18 will be home in the socket 21 and the finger 25 will pass up along the surface 30 thus returning the parts to the lock position. 15 shown in Fig. 1. When in this position the door cannot be opened except by depressing the plunger 13.

While we have described our device in considerable detail it will be obvious that 20 many changes in these details and arrangement of parts may be made without departing from our invention and we do not, therefore, desire to be considered as limited to the precise form shown and described.

25 Having thus described our invention what we claim and desire to secure by Letters Patent is:

1. In a device of the class described, a latch and keeper, said latch comprising a 30 spring pressed member projecting therefrom, an oscillating finger in position to engage the rear of said member in normal position of the device, a plunger connected to said finger to depress the same, a spring 35 tending to resist such action and tending to return both the plunger and finger to normal position after the same have been depressed, and means carried by said plunger adapted to engage a portion of said keeper 40 to depress said plunger as said latch approaches said keeper.

2. In a device of the class described, a latch and keeper, said latch comprising a 45 spring pressed knob projecting therefrom, an oscillating finger in position to engage the rear of said knob in normal position of the device, a plunger connected to said finger, an operating handle or knob carried by 50 said plunger and arranged for manually depressing the plunger and finger, a spring tending to resist such action, and a finger carried by said plunger adapted to engage a portion of said keeper to depress said plunger as said latch approaches said 55 keeper.

3. In a device of the class described, a latch and keeper, said latch comprising a 60 spring pressed knob projecting therefrom, an oscillating finger in position to engage the rear of said knob in normal position of the device, a plunger pivotally connected to 65 said finger to depress the same, a spring tending to resist such action and tending to return both the plunger and finger to their normal position after the same have been

depressed, and a finger rigidly carried by said plunger and adapted to engage a cam lug on said keeper as said latch approaches said keeper.

4. In a device of the class described, a 70 latch and keeper, said latch comprising a spring pressed knob projecting therefrom, an oscillating finger in position to engage the rear of said knob in normal position of the device, a plunger connected to said finger, an operating handle or knob carried by 75 said plunger and arranged for manually depressing the plunger and finger, a spring tending to resist such action, and a finger rigidly carried by said plunger, said keeper comprising a recess adapted to receive said knob and a cam lug adapted to engage said last mentioned finger to depress said plunger and free said knob to movement against its spring. 80

5. In a device of the class described, a latch and keeper, said latch comprising a spring pressed knob projecting therefrom, an oscillating finger in position to engage the rear of said knob in normal position of the device, a plunger connected to said finger to depress the same, a spring tending 85 to resist such action, and a finger rigidly carried by said plunger, said keeper comprising a recess adapted to receive said knob and a cam lug shaped to engage said last mentioned finger to depress said plunger, to retain said plunger depressed for a certain length of travel, and then to permit said finger to rise behind the said lug. 90

6. In a device of the class described, a latch and keeper, said latch comprising a face plate having an opening therein, a knob, a leaf spring secured to said face plate at one end and mounting said knob at its free 105 end in position to project through the opening in the face plate, a rotatable spindle having a finger projecting therefrom in position to engage the rear of said spring, a plunger connected to said finger to depress the same, a spring tending to resist such action, and a finger rigidly carried by said plunger, said keeper comprising a recess adapted to receive said knob and a cam lug adapted to engage said last mentioned finger to depress 110 said plunger, to retain said plunger depressed for a certain length of travel, and then to permit said finger to rise behind said lug. 115

7. In a device of the class described, a 120 latch and keeper, said latch comprising a member resiliently projected therefrom, an oscillating finger in position to engage said member in normal position of the device to lock the same in projected position, a plunger connected to said finger to move the finger from and into the path of said member, a spring tending to resist the movement of said finger from the path of said member, and means carried by the plunger 125 130

adapted to engage a portion of said keeper to shift said plunger as said latch approaches said keeper.

8. In a door lock, the combination with a casing, of a plunger movable in said casing and having a part projecting therefrom, a locking member projecting from said casing, releasable locking means whereby said member is locked in its projected position, a spring for actuating said plunger and said means and tending to move the latter into position to lock said member, means for retaining said locking means in its unlocked position while the door is being closed, said retaining means being arranged to be released to permit the operation of said plunger and locking means by said spring, when the door is finally closed.

9. In a door lock, the combination with a casing, of a locking member normally pro-

jecting therefrom, a plunger having a part thereof disposed within said casing, an operating handle or knob carried by said plunger and arranged for manually operating the same, means, comprising a part movable with the plunger, for locking said member in its projected position, a spring for moving said plunger and locking means into locking position, and a keeper-operable means for retaining said locking means in its unlocked position while the door is being closed, but arranged to be released to permit said plunger and locking means to be operated by said spring, when the door is finally closed.

In testimony whereof we have hereunto affixed our signatures.

EDWIN CROMPTON.
CHARLES L. CROOKS.
